US00D495054S1

(12) **United States Design Patent** (10) Patent No.: **US D495,054 S**
(45) Date of Patent: **** Aug. 24, 2004**

(54) **CANNULA HEAD**

(75) Inventors: **Deborah A. Laun**, Syracuse, NY (US);
Daniel M. Wing, Utica, NY (US);
Frank J. Witkowski, Syracuse, NY
(US)

(73) Assignee: **Conmed Corporation**, Utica, NY (US)

(**) Term: **14 Years**

(21) Appl. No.: **29/180,774**

(22) Filed: **Apr. 28, 2003**

Related U.S. Application Data

(60) Division of application No. 29/168,574, filed on Oct. 4, 2002, and a division of application No. 10/264,530, filed on Oct. 4, 2002, which is a continuation-in-part of application No. 09/944,190, filed on Aug. 31, 2001.

(57) **CLAIM**

The ornamental design for a cannula head, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is an isometric view of a cannula head in accordance with the new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines in the figures are for illustrative purposes only and form no part of the claimed design.
